UNITED STATES PATENT OFFICE.

JOSEPH W. AMRATH, OF SAN FRANCISCO, CALIFORNIA.

TEMPORARY BINDER.

SPECIFICATION forming part of Letters Patent No. 764,266, dated July 5, 1904.

Application filed May 14, 1903. Serial No. 157,128. (No model.)

To all whom it may concern:

Be it known that I, JOSEPH W. AMRATH, a citizen of the United States, residing at San Francisco, in the county of San Francisco and State of California, have invented certain new and useful Improvements in Temporary Binders, of which the following is a specification.

My invention relates to temporary binders, but is intended more particularly for use as a transfer-file for keeping in proper order and sequence the leaves or cards which form the fillings of so-called "loose-leaf" ledgers.

The object of my invention is to furnish a cheap, simple, and convenient device for receiving and retaining for as long as may be desired these cards or leaves transferred from a ledger.

A practical embodiment of my invention is shown in the accompanying drawings, in which—

Figure 1 is a side elevation of the complete device in its locked position. Fig. 2 is a plan view with the upper plate of the guide-frame removed. Fig. 3 is a cross-section on line xx of Fig. 2. Fig. 4 is a cross-section on line yy of Fig. 2.

1 represents a base-plate, in which are secured any suitable number of vertical rods 2, two of which are shown in the drawings. Fitted upon these screws is a clamp, which is adapted to be pressed down upon the leaves or cards strung upon the screw-rods. The clamp can be entirely removed from the rods, so that if the leaves have perforations within their edges such leaves can be threaded upon the rods after the clamp has been taken off. In many loose-leaf ledgers, however, the leaves are provided with key-shaped slots producing the effect of interior perforations, which are open to an edge of the card by means of relatively narrow passages. Cards like these can be fitted to the holding-rods by a sidewise movement, making it unnecessary to remove the clamp. When the desired number of cards are in place, the clamp is pressed down upon them and is locked to the said rods. The clamp is composed of two members 3 4, which may be separate strips of metal or, as shown in the drawings, may be a single strip bent upon itself and having its free ends remov-

ably secured together by a distance-piece 5. The parallel members 3 4 form a guide, in which the locking device is movable. The rods 2 pass through the clamp at one side of its middle line, leaving room for the longitudinal cam-shaft 6, which is journaled in the ends of the clamp and may also be cut away, as shown at 7, to bear within slots in the intermediate distance-pieces 8. The end of the cam-shaft projects beyond the clamp and is provided with a handle 9. It has no longitudinal movement, but can be turned in either direction, so as to bring the cam-faces 10 against the rods 2 or to withdraw them from such contact. In the former case the clamp is locked upon the rods at any distance from the base; but in the latter event it is released and can be moved freely on the guide-rods, enabling it to be pressed down upon the leaves and then locked. I have shown three sections of cam-faces in the drawings and two guide-rods; but it will be understood that as many guides and cams can be provided as may be required by the size of the leaves. It will be observed that the rods are smooth-surfaced and not threaded, so that there is no interference with the free sliding adjustment of the clamp, the latter being rigid and preventing any binding action.

I prefer to make the guide-rods 2 in several sections, as shown, in order to increase the capacity of the file for holding leaves as great as may be necessary. Each section is provided at one end with a screw-threaded stub end fitting a screw-threaded socket in the end of the adjacent section, the last section being closed by a cap 12, which fits all the end sockets. Each section may also have a hole 13 to receive a turning-pin. I thus provide extensible and contractible smooth-surfaced rods, which can be locked by the cam-shaft at any point in their length.

Having thus fully described my invention, what I claim as new, and desire to secure by Letters Patent, is—

1. A temporary binder comprising a plate, guide-rods secured therein, a clamp adjustable upon said rods and a cam-shaft journaled longitudinally in the clamp and adapted to be turned in both directions so as to bear upon

and lock said clamp to the rods, or to release said clamp from the rods.

2. A temporary binder comprising a plate, guide-rods secured therein a clamp having two parallel plates, through both of which such rods pass, a shaft journaled between said plates and cam-faces on said shaft adapted to bear upon said rods and thereby lock said clamp.
- 10 3. A temporary binder comprising a base, vertical guide-rods secured thereto, a clamp adjustable on said rods, a horizontal shaft

journaled in the clamp at one side of said guide-rods, and cam-surfaces on said shaft adapted to bear upon said rods so as to lock the clamp thereto.

In testimony whereof I have affixed my signature, in presence of two witnesses, this 31st day of May, 1902.

JOSEPH W. AMRATH.
